UNITED STATES PATENT OFFICE.

JESSE BRAMBLE, OF EVANSVILLE, INDIANA, ASSIGNOR TO THE GRAHAM GLASS COMPANY, OF EVANSVILLE, INDIANA, A CORPORATION OF INDIANA.

DESIGN FOR A BOTTLE OR THE LIKE.

Application filed May 25, 1928. Serial No. 26,849 Term of patent 14 years.

To all whom it may concern:

Be it known that I, JESSE BRAMBLE, a citizen of the United States, residing at Evansville, in the county of Vanderburg, State of Indiana, have invented a new, original, and ornamental Design for a bottle or the like.

The ornamental band is the essential feature of the design, and accordingly a conventional bottle is denoted by the dotted line in the drawing.

The drawing shows a side elevation of a conventional beverage bottle in dotted lines, with the ornamentation design applied thereto.

I claim:

The ornamental design for a bottle or the like substantially as shown and described.

JESSE BRAMBLE.
